AUXILIARY WINDOW SASH

Hans Radomski, Richmond Hill, N. Y., assignor
of one-half to Herbert Andreas, Ridgewood,
N. Y.

Application February 6, 1953, Serial No. 335,439

7 Claims. (Cl. 20—42)

1

This invention relates to new and useful improvements in auxiliary windows. It is particularly concerned with an auxiliary window sash of a type the organization and arrangement of which enables its use on the inner or room side of a window frame of a building.

The invention finds particular use with picture window structures, such as are commonly associated with ranch type and bungalow homes, though it may well be used with other type window structures. The picture window generally includes a large lower area which is fixed and does not open. Above this area are one or more smaller window frames, each about 20 x 30 inches, the sash of which are arranged to swing outward to an open position to provide room ventilation. Because these swing outward to open, they provide many difficulties, especially in the colder months when ventilation as well as storm protection is desired.

When they are covered over from the outside by a storm window, they cannot swing outward when desired for ventilation or other purpose. No practical solution appears to have been provided for this difficulty. The same difficulties arise during the summer months when it is desired to provide screened ventilation for such windows. An auxiliary sash is desired that may be adapted for either winter or summer use, particularly of a type that will enable the regular window sash to be opened when desired without difficulty for cleaning, ventilation or other purpose.

Now, I have invented an auxiliary window sash arrangement which can be used in conjunction with the type of windows mentioned in all seasons, and which eliminates in a practical manner the difficulties mentioned. Further, the invention has wide application and may be used with window frames of various constructions.

The invention proposes an auxiliary window sash of practical construction which can be used in conjunction with the regular sash of a frame and is adapted for use on the room side thereof. It is arranged with appropriate linkage or hardware, so that, when desired, it may be opened in the direction of the inside of a room and thereby provide access to the regular window sash for cleaning, replacement, ventilation or other purpose.

A feature of the auxiliary sash proposed is that it not only opens into the inside of a room, but it is so arranged that when opened it may be lowered into the room for purposes of cleaning, repairs, or otherwise.

Another feature of the auxiliary sash is that

2

it is adapted to receive a glass or screen panel closure, as desired, and these are readily interchangeable the one with the other.

A general object of the invention is, therefore, 5 an auxiliary window sash of practical construction that is operable to an open or closed position from the inside of a room.

Another object of the invention is an auxiliary window sash for a window opening, which is 10 adapted for winter or summer use and may be arranged and opened on the inside of the window opening.

A further object of the invention is attaching means associated with an auxiliary window 15 sash whereby the sash may be arranged in the window frame of a building and opened or closed from the room side of a window frame.

The foregoing objects and advantages of this 20 invention, as well as many others, will become readily apparent as this specification unfolds in greater detail and as it is read in conjunction with the accompanying drawings forming a part of this application and wherein a preferred embodiment of the invention is illustrated.

25 In the drawings:

Fig. 1 is a front elevational view of a window frame of a building in association with which the invention is shown;

Fig. 2 is a vertical cross section taken about 30 midway of Fig. 1;

Fig. 3 is a view of the left end of the auxiliary sash in Fig. 1 on a larger scale;

Fig. 4 is a detail of the connecting hardware 35 apart from the auxiliary sash and in normal position;

Fig. 5 is a further detail of the connecting hardware but in an operative position;

Fig. 6 is a top plan view of the left end of 40 Fig. 1 on a larger scale and with parts cut away;

Fig. 7 is a large scale end view of Fig. 1 with 45 parts cut away and showing the auxiliary sash in partial and full open positions.

In the drawings, wherein identical parts are referred to by the same reference numbers, there is disclosed in the window opening of a building 1 a frame 2 having top, bottom and side walls, respectively 3, 4 and 5. Frame 2 includes a regular window sash 6, hereof of a type which is hinged at the top to the frame and is arranged to swing out and rearwardly at the bottom to an open position, as indicated by the broken line 7 in Fig. 2. When in closed position the regular window sash 6 abuts against a rabbet 8 of the window frame 3. Longitudinally of the inner faces of frame walls

3, 4 and 5, along about the center thereof, is a sash stop moulding 9. On the forward or room side of frame 2 is arranged an auxiliary sash frame 10, which when in a closed position, Fig. 2, abuts against the forward sides of the stop moulding.

Sash 10 includes top, bottom and side rails, respectively designated 11, 12 and 14. Longitudinally of the top side of the bottom rail 12 is a channel 15; a similar channel 16, but of a greater depth is provided longitudinally of the underside of the top sash rail 11. A frame 18, here carrying a glass panel 19, is removably received between the several rails of sash 10 and has its upper transverse strip 20 in the upper channel 16, and its lower transverse strip 21 in the lower channel 15. Frame 18 is held in the channels by the rear and forward lips 22 of the channels. The sash side rails 14 each include a rear inwardly extending lip 23, serving to further support panel frame 18 at the rear. Panel frame 18 is of a height slightly less than the distance existing between the channels 15 and 16, and it may be removed from the channels by first lifting it upwards to the limits of the upper channel 16 so as to free the lower strip 21 of the panel frame from the lips 22 of the lower channel 15. The frame 18 is then drawn forwardly and out of the auxiliary sash 10.

The auxiliary sash 10 is associated with the regular frame 2 in such manner that it may be drawn from a position closing the room side of the window opening to a position removed from the frame, though still connected to it, and when so removed from the frame it may be suspended in the room before the window opening in a lowered position, as in Fig. 7. In the latter position full access is afforded through the building frame 2 to the regular window sash 6 for purposes of ventilation, cleaning or otherwise. To this end each side rail 14 of the auxiliary sash is individually provided with suitable linkage, generally designated 24, associating it with a corresponding side wall 5 of the building frame 2. The manner and means by which each side rail 14 is associated with its corresponding frame wall 5 is the same, and what is described as to one applies to the other.

The linkage 24 and the manner of associating a side rail 14 with a corresponding side wall 5 of the frame 2 includes an angle bracket 25, from the central area of a plate 26 of which extends at right angles a short pin 27 on which a pair of links 28 and 29 are arranged to pivot. Link 28 comprises a pair of elongated rectangular walls 30 in parallel spaced relation to one another and integrally joined to each other by a back portion 31, whereby a knifeway 32 is provided between the free ends of the walls. Link 28 pivots upon the pin 27 which passes through the lower ends of both walls 30. Link 29 in the manner of a blade pivots at one end on pin 27 between the walls 30 of link 28. A coil spring 33 carried about pin 27 and having its free ends connected to links 28 and 29 serves to constantly tension these in opposite directions. In this arrangement a free end 34 of the coil spring is anchored in an aperture of a pin 35 projecting from a face of link 28, the other end 36 of the spring is anchored in a similar pin 35 on a face of the blade link 29.

Links 28 and 29 are preferably of equal length, and at the free end of each is means engageable in a channel member 37 for up and down slideable movement in the latter. To this end, at the free end of link 28 on the outer face of the outer

wall 30 thereof extends at right angles a stud, the shank 38 of which terminates in an enlarged disc 39. Projecting from the outer face of link 29 at the free end thereof and at right angles thereto is a similar stud the shank 40 of which terminates at its free end in an enlarged disc 41 similar to disc 39.

Discs 39 and 41 are engaged in a channel 42 of the channel member 37 and are adapted for up and down slideable movement therein, one above the other. Channel bar 37 includes an elongated back plate portion 43, the free longitudinal ends 44 of which are bent around to a position short of one another in front of the back plate where they are spaced away from the latter so as to form the channel 42 and to form an elongated opening 45 between the ends 44. The shanks 38 and 40 of the respective discs 39 and 41 extend from the latter freely through the opening 45 to their respective links. The channel ends 44 overlap the discs and serve to confine them to the channel. The arrangement is such that links 28 and 29 in normal position are held under tension of coil spring 33 in opposite directions, so that the link ends are 180 degrees apart, the disc 39 is extended vertically upward in the channel bar, while the disc 41 is extended downward in the opposite direction. The channel bar 37 is adapted to be fixed as in Figs. 3, 6 and 7 in a vertical position against the inner face of a side wall 5 of frame 2 adjacent to the stop moulding 9. The channel bar extends in height from the base of frame 2 to the top wall thereof. It is secured to the inner face of wall 5 in suitable manner, such as by screws through holes 46 in the channel back. The channel opening 45 faces away from the wall into the frame opening. The angle bracket 25 is adapted to be fixed by suitable fasteners to the outer face of a side rail 14 of the auxiliary sash 10 at a distance below the top of the rail so that link 28 when extended to its uppermost position in the channel will not extend above the top rail of the sash.

To enable the auxiliary sash 10 to be received between walls of frame 2 without having a space between the sides of the sash and the walls 5 of frame 2, as would otherwise happen because of the room taken up by the linkage 24 at the sides of the sash, the outer faces of each side rail 14 is angularly recessed longitudinally of a corner thereof as at 47, in such manner as to accommodate therein bracket 25, links 28 and 29 and the associated channel bar when the sash 10 is in a position closing the frame 2, Figs. 3, 6, and 7. Bracket 25 includes a second plate 50 whereby the bracket is secured in the recess 47 by suitable screws 51 to the sash.

Now, in the manner of operating the arrangement it can readily be seen that when sash 10 is in its closed position in frame 2 and it is desired to withdraw it to its open position outside of the frame, it is held by the handgrips 48 and is drawn inwardly at the bottom toward the person, as in Fig. 7, to a position beyond the edge of the frame sill. Downward pressure is then exerted upon the sash to lower it. The sash is uniformly guided in its downward movement by the discs 39 and 41 which are carried down in the channel bars at the side walls 5 as the sash is lowered. When the lower disc 41 in each channel limits against the base of the frame and the associated links 28 and 29 have substantially knifed into one another, the sash will be limited in its downward movement and will hang suspended before the frame within the room of the

building. In the latter position the auxiliary sash may be cleaned or otherwise attended to and access is provided from the inside of the room to the regular window 6 for appropriate attention.

The auxiliary sash may be restored to its closed position by lifting it upwards so as to raise the discs in the side channels. As the discs are carried upwards the sash will be uniformly guided in its upward movement. In restoring the sash to closed position, it is preferably raised with the upper portion thereof inclined towards the top of frame 2. It is lifted in this direction until the top rail of the sash engages behind a narrow transverse moulding strip 49 affixed to the underside of the top wall of frame 2. The bottom of the sash will at this time be slightly above the sill 4 of frame 2. When the latter position is reached, the sash is then pushed back at the bottom to bring it to closed position. The narrow moulding strip 49 prevents the sash from moving forward at the top when the bottom portion thereof is being pushed backwards into the frame to closing position.

From the foregoing arrangement of the auxiliary sash with the frame 2 and its manner of operation, a further advantage is evident, in that the sash can be moved from a closed to an open position without interference with shade rollers or Venetian blind structures that might be positioned at the upper forward portion of frame 2.

While I have described and illustrated a preferred form of the invention, it is clear that some modifications of form might be made without departing from the spirit of the invention, and it is my intent, therefore, to claim the invention not only in the form presented, but also in all such forms as may be reasonably construed to be within the spirit of the invention and scope of the appended claims.

I claim:

1. Means for attaching an auxiliary sash to a window frame comprising, a pair of links pivotable at one end upon a common pivot, bracket means carrying the common pivot and adapted to be secured to a side rail of the auxiliary sash, a channel bar adapted to be fixed in a vertical position to a side wall of the window frame, discs one at the free end of each link engaged in the channel bar and adapted for up and down sliding movement therein, and a spring carried by the common pivot constantly tensioning the links in opposite directions.

2. Means for attaching an auxiliary sash to a window frame of a building comprising at each side rail of the auxiliary sash linkage joining

the side rail with a corresponding wall of the window frame, the linkage comprising a pair of links pivotable at one end upon a common pivot, bracket means including the common pivot

5 adapted to be secured to a side rail of the auxiliary sash, a channel bar adapted to be fixed in a vertical position to a side wall of the window frame, discs, one at the free end of each link engaged in the channel bar and adapted for up and down sliding movement therein, and a spring carried by the common pivot constantly tensioning the links in opposite directions.

3. The combination of a window frame, an auxiliary sash and linkage at each side rail of 15 the sash connecting the rail with a corresponding side wall of the frame, the linkage at each side rail being identical and comprising a pair of links pivotable upon a common pivot at one end in parallel relation to one another, a bracket 20 including the common pivot and secured to the outer side of a side rail of the auxiliary sash, a channel member including a channel secured in a vertical position against the inner face of a side wall of the frame, slide elements, one at the 25 free end of each link engaged in the channel and adapted for up and down sliding movement therein toward and away from one another, and a spring carried on the pivot arranged to constantly tension the free ends of the links and the 30 associated slide elements in opposite directions from one another.

4. The combination as in claim 3, wherein the links are of equal length and one includes a knifeway into which the other is adapted to pivot when the slide members of the links are moved toward one another.

5. The combination as in claim 3, wherein the links are tensioned by the coil spring to a position 180 degrees apart when the auxiliary sash 40 is in a position closing the frame.

6. The combination as in claim 3, wherein the spring is wound about the pivot pin and one end of the spring is anchored to one of the links and the other end is anchored to the other link.

7. The combination as in claim 3, wherein the auxiliary sash includes in its side rails angular recesses adapted to accommodate the linkage when the sash is in a position closing the window frame.

50 HANS RADOMSKI.
